CLAIM

The ornamental design of an automotive power seat switch, as shown and described.

DESCRIPTION

FIG. 1 is a front perspective view of an automotive power seat switch showing my new design;

FIG. 2 is a top plan view thereof;

FIG. 3 is a right side elevational view thereof;

FIG. 4 is a left side elevational view thereof;

FIG. 5 is a front perspective view of a second embodiment thereof; and

FIG. 6 is front perspective view of a third embodiment thereof.

The undisclosed top and sides of the second and third embodiment are the same as FIGS. 2-4.

FIG. 1

FIG. 2

FIG. 3

FIG. 4

FIG. 5

FIG. 6
